UNITED STATES PATENT OFFICE.

LEVI JARVIS, OF CEDAR RAPIDS, NEBRASKA.

HOE.

1,374,740.

Specification of Letters Patent. Patented Apr. 12, 1921.

Application filed September 4, 1919. Serial No. 321,511.

To all whom it may concern:

Be it known that I, LEVI JARVIS, a citizen of the United States, residing at Cedar Rapids, in the county of Boone and State of Nebraska, have invented a new and useful Hoe, of which the following is a specification.

The device forming the subject matter of this application is a hoe, and one object of 10 the invention is to provide a device of the kind alluded to in which the effective length of the structure, measured from the blade, may be adjusted at will.

Another object of the invention is to provide 15 novel means whereby the blades of the hoe may be interchanged.

A further object of the invention is so to construct the hoe that the blade will operate at a very small angle with respect to 20 the surface of the soil, thereby rendering it unnecessary to raise the hoe to a considerable height, and make a stroke, during the operation of weeding.

It is within the province of the disclosure 25 to improve generally and to enhance the utility of devices of that type to which the invention appertains.

With the above and other objects in view, 30 which will appear as the description proceeds, the invention resides in the combination and arrangement of parts and in the details of construction hereinafter described and claimed, it being understood that, within the scope of what is claimed, changes in the 35 precise embodiment of the invention shown can be made without departing from the spirit of the invention.

In the accompanying drawings:—

Figure 1 shows in side elevation, a device 40 constructed in accordance with the invention, parts being broken away; Fig. 2 is a top plan wherein the blade has been omitted; Fig. 3 is a cross section on the line 3—3 of Fig. 1; Fig. 4 is a plan showing the 45 blade; Fig. 5 is a plan showing a modified form of blade; and Fig. 6 is a fragmental longitudinal section taken through the member which receives the blade-carrying shank.

In carrying out the invention, there is 50 provided a handle holder 1, which may be in the form of a socket, adapted to receive a handle H. The holder 1 has a downwardly offset arm 2, merging into a base 3 disposed approximately parallel to the axis of the 55 holder, the base 3 being supplied at its outer end with an eye 4. A bore 5 extends longi-

tudinally of the base 3 and is prolonged through the arm 2 and through the eye 4, as clearly indicated in Fig. 6. In the top of the eye 4 there is an opening 8 wherein a 60 screw 7 is threaded. An opening 6 is fashioned in the top of the base 3, between the arm 2 and the eye 4 and communicates with the bore 5.

The invention comprises a shank including 65 a body 9 and a flattened foot 10 disposed at an angle to the body. The numeral 11 denotes a blade having openings 12 adapted to receive securing elements 14 whereby the blade may be secured to the foot 10. The 70 blade may include a rectangular main portion 15 and a blunted triangular extension 16. The blade 11 may be used interchangeably with a blade 17 of blunter triangular form. The blade 17 has openings 18 adapted 75 to receive the securing elements 14.

In practical operation, one end of the body portion 9 of the shank is received in the bore 5, the set screw 7 being tightened up until it bears against the member 9. 80 The member 9 may be adjusted longitudinally with respect to the handle holder 1, and in this way, the effective length of the handle H may be adjusted, thereby to position the blade 11 properly with respect to 85 the soil. The opening 6 serves to let dirt out of the bore 5 and to render the longitudinal adjustment of the member 9 relatively easy. Further, if the member 9 should become rusted in the bore 5, oil may 90 be introduced into the bore, by way of the opening 6. The angle between the part 9 of the shank and the foot 10 thereof is approximately fifty degrees, and by adjusting the part 9 longitudinally of the handle 95 holder 1, the structure may be so regulated that, when it is used by a person of ordinary stature, the blade 11 will be disposed at a very slight angle, say five degrees, with respect to the surface of the soil. It will 100 be obvious that when the blade 11 is located as above described, and as shown in Fig. 1, the blade operates in approximate parallelism with the surface of the soil, it being possible to carry out the weeding operation 105 without effort on the part of the operator, there being no occasion for raising the blade 11 to a considerable height and making a positive downward stroke. The blades 11 and 17 are sharpened along all of their 110 edges, as shown at 19, and, consequently, a cutting stroke may be made effectively in

any direction, either backwardly or forwardly, or sidewise.

Having thus described the invention, what is claimed is:—

- 5 In a hoe, a handle holder having a downwardly offset arm merging into a base disposed approximately parallel to the axis of the holder, the base being supplied at its outer end with an eye, and having a bore of
- 10 common diameter from end to end, the bore being prolonged through the arm and through the eye, there being an opening in the top of the base, between the arm and the eye, the opening communicating with the bore; a shank including a body slidable in
- 15

the bore and spaced transversely from the holder for free longitudinal sliding movement in spaced relation to the holder; a blade carried by the shank; and a clamping device mounted in the eye and engaging the body, the clamping device constituting the sole means for limiting the longitudinal movement of the body.

In testimony that I claim the foregoing as my own, I have hereto affixed my signature in the presence of two witnesses.

LEVI JARVIS.
